UNITED STATES PATENT OFFICE.

EULALIA CUTBIRTH, OF BIG LAKE, TEXAS.

PACKAGE TIE.

Application filed May 7, 1919. Serial No. 295,484.

To all whom it may concern:

Be it known that I, EULALIA CUTBIRTH, a citizen of the United States, and a resident of Big Lake, in the county of Reagan and State of Texas, have invented certain new and useful Improvements in a Package Tie, of which the following is a specification.

This invention relates to package ties, and an object of the invention is to provide a package tie which may be used a number of times, and which is constructed so as to facilitate its tying about a package, or its removal therefrom.

More specifically, the invention comprehends the provision of a package tie comprising a relatively long cord having a loop formed at one end thereof, upon which cord is slidably mounted a cylindrical sleeve, tapering at its end which is adapted for insertion through the knot in the cord, when tied about a package, to facilitate the untying of the knot and the resulting removal of the package tie from the package.

Other objects of the invention will appear in the following detailed description, taken in connection with the accompanying drawing, forming a part of this specification, and in which drawing:

Figure 1 is a view illustrating the package tie.

Figure 2 is a view illustrating the package tie in the first step of positioning it about a package.

Figure 3 illustrates a second or subsequent step in the placing of the tie about a package.

Figures 4, 5 and 6 illustrate the second step in the tying of the package tie about a package.

Figure 6 showing the completed knot.

Referring more particularly to the drawing, 10 indicates the cord which forms the main portion of the package tie, this cord is looped and tied at one end to provide the loop 11, after it has a sleeve 12 slidably mounted thereon, which sleeve gradually tapers toward each end, as clearly shown in Fig. 1 of the drawing. The end of the cord remote from the end upon which the loop 11 is formed is knotted, as shown at 13, to pre-

vent the sleeve 12 from passing off the end of the cord.

In placing the improved package tie about a package, it is first passed about the package in one direction, preferably longitudinally thereof, with the loop 11, at the center of one side of the package, after which the knotted end 13 of the cord is passed through the loop and about the package indicated at A, transversely to the direction in which it was originally passed about the package, thus forming a tie over all four of the edges of the package to securely confine the contents thereof.

After the cord has been passed entirely about the package, the free end which carries the knot 13 is inserted through the loop 11, and passed under the portion of the cord which leads up to the said loop 11, to provide a second loop and it is then swung over the said portion which is indicated by the numeral 14 in the drawing, to provide a third loop and passed through the third loop as clearly shown in Fig. 4 of the drawing. After the end of the cord 10 has been passed through the second loop, as shown in Fig. 4 of the drawing, it is returned through the third loop formed by the portion of the cord which is passed under the length or portion 14 thereof and the portion of the cord which is inserted through the second loop formed at the loop 11 as shown in Fig. 5 of the drawing.

The knot, formed by the two loops which are in turn formed by the passing of the free end of the cord 10 under and over the portion 14 thereof is drawn tight with the sleeve 12 in the knot, or if it is so desired, the sleeve 12 may be inserted through the knot after it has been drawn tight, owing to the tapering at its end portion, thus permitting the free and easy untying of the knot and consequently allowing the package tie to be re-used.

Changes in details may be made without departing from the spirit of this invention, but;

I claim:

A package tie comprising a cord having

one end provided with a loop for receiving a portion of the cord when the cord is placed about a package and tied, and a threading sleeve having a longitudinally extending bore to receive the cord, said sleeve being slidably mounted upon the opposite end portion of the cord from the loop and

adapted to be secured in a knot formed when the cord is secured about a package, and said sleeve being tapered towards its ends to facilitate passage of the sleeve through a knot formed in securing the cord about a package. 10

EULALIA CUTBIRTH.
